No. 36,463.

Patented July 28, 1903.

UNITED STATES PATENT OFFICE.

PHILEMON O. DICKINSON, OF NEWARK, NEW JERSEY, ASSIGNOR TO UNGER BROTHERS, OF NEWARK, NEW JERSEY, A COPARTNERSHIP.

DESIGN FOR A HANDLE FOR NAIL-FILES OR SIMILAR ARTICLES.

SPECIFICATION forming part of Design No. 36,463, dated July 28, 1903.

Application filed June 27, 1903. Serial No. 163,445. Term of patent 3½ years.

To all whom it may concern:

Be it known that I, PHILEMON O. DICKINSON, a citizen of the United States, residing at Newark, county of Essex, and State of New Jersey, have invented a certain new, original, and ornamental Design for a Handle for a Nail-File or Similar Article, as illustrated in the accompanying drawing, which shows a perspective view of the same.

What I claim is—
The ornamental design for a handle for a nail-file or similar article as herein shown.

PHILEMON O. DICKINSON.
